(57) **CLAIM**

The ornamental design for a garden edging, as shown and described.

DESCRIPTION

FIG. 1 is a front perspective view of a garden edging in use, showing my new design;

FIG. 2 is a rear perspective view thereof;

FIG. 3 is an exploded front perspective view thereof;

FIG. 4 is an exploded front elevational view thereof, the rear elevational view being a mirror image thereof;

FIG. 5 is an exploded left-side elevational view thereof, the right-side elevational view being a mirror image thereof;

FIG. 6 is an exploded top plan view thereof; and,

FIG. 7 is an exploded bottom plan view thereof.

The dash-dash broken lines showing a garden in FIGS. 1 and 2 illustrate environmental matter that forms no part of the claimed design. The remaining broken lines in the figures depict portions of the garden edging system as well as symbolic break lines, and any portion in between them, that form no part of the claimed design. The dot-dash broken lines represent boundaries of the claim and form no part thereof.

1 Claim, 5 Drawing Sheets
